(57) **CLAIM**

The ornamental design for a strap wrench, as shown and described.

DESCRIPTION

FIG. 1 is an elevated perspective view of a body element thereof;

FIG. 2 is a top plan view of a body element thereof;

FIG. 3 is a bottom plan view of a body element thereof;

FIG. 4 is a first side elevational view of a body element thereof;

FIG. 5 is a second side elevational view of a body element thereof;

FIG. 6 is an elevated perspective view of a body element and cradle element thereof;

FIG. 7 is a top plan view of a body element and cradle element thereof;

FIG. 8 is a bottom plan view of a body element and cradle element thereof;

FIG. 9 is a first side elevational view of a body element and cradle element thereof;

FIG. 10 is a first end elevational view of an assembled tool thereof;

FIG. 11 is a second end elevational view of an assembled tool thereof; and,

FIG. 12 is a side elevational perspective view of an assembled tool showing an exemplary wrench driver thereof.

The broken lines in a drawing illustrate environmental structure and portions of the design that forms no part of the claimed design.
